UNITED STATES PATENT OFFICE

2,088,582

STEAM MOTOR

Carl Emmit Bishop, Carlisle, Iowa

Application December 16, 1933, Serial No. 702,746

5 Claims. (Cl. 121—112)

An object of my invention is to provide a motor of simple, durable and inexpensive construction for operating on steam or other expansible fluid pressure.

5 A further object is to provide a motor especially adapted for high pressure and high temperature steam for automotive use, such as on automobiles, tractors, aeroplanes, motor boats, rail cars and the like where a considerable amount 10 of power must be generated, but the space for the motor is limited and it is also desirable to minimize the weight of the motor in proportion to the horse-power delivered by it.

A further object is to procure an ultimate expansion of steam by a novel compounding construction of the motor, yet get extreme torque or turning power for starting purposes, especially when the start must be made under load, as required by many types of automotive equipment, 20 and control of the motor and the vehicle is simultaneously effected by a throttle without the use of a clutch or transmission.

A further object is to provide an expansible fluid pressure motor of few parts and from which 25 stuffing boxes, eccentrics, reversing linkage and the like commonly found in connection with steam engines are entirely eliminated, yet greater expansion of the fluid pressure, increased economy and a maximum of efficiency are obtained with a 30 motor having a low enough unit of weight per horse-power to be suitable for aeronautical purposes.

Still another object is to provide a compound 35 type of motor in which steam from a high pressure cylinder is transferred directly through a short passageway and a valve to a low pressure cylinder, the pistons in these cylinders being so connected with the power shaft that they always reciprocate in opposite directions, thus making 40 it possible to simultaneously exhaust steam from the high pressure cylinder and into the low pressure cylinder without any intermediate receiver or the like as usually associated with compound steam engines and which always present a problem 45 of heat loss and consequently decreased efficiency.

Another object is to provide a steam motor of compound type in which the parts are all balanced, the cylinders being arranged radially 50 around a power shaft and the reciprocating pistons in the high and low pressure cylinders always reciprocating in opposite directions so as to minimize vibration which has its greatest tendency to occur at high speed of the motor.

55 Another object is to so associate the elements

of a steam motor together that a turbine-like action or an action in which a smooth evenly applied torque throughout each degree of each entire revolution is produced in rotating the power shaft.

Still another object is to provide novel details of construction whereby the valve action is controlled partly manually and partly automatically.

Another object is to provide packingless valves 10 of special poppet construction applied in a manner which is novel as far as steam engines of the ordinary type are concerned.

With these and other objects in view my invention consists in the construction, arrangement and combination of the various parts of my 15 device, whereby the objects contemplated are attained, as hereinafter more fully set forth, pointed out in my claims, and illustrated in the accompanying drawings, in which:

Figure 1 is an end elevation of a steam motor 20 embodying my invention.

Figure 2 is a diagrammatic end view of the motor to show the relation of the high and low pressure pistons to each other and to the power shaft.

Figure 3 is a sectional view on the line 3—3 of 25 Figure 1, showing an inlet valve and a transfer valve.

Figure 4 is a sectional view on the line 4—4 of Figure 1 showing an exhaust valve.

Figure 5 is a sectional view on the line 5—5 of 30 Figure 3 showing an inlet valve cam.

Figure 5A is a sectional view similar to Figure 5 showing a modified shape of cam.

Figure 6 is a similar sectional view on the line 6—6 of Figure 3 showing a lost motion transfer valve cam and an exhaust valve cam.

Figure 7 is a similar sectional view on the line 1—1 of Figure 3 showing a lost motion exhaust valve cam.

Figure 8 is a sectional view on the line 8—8 of 40 Figure 1 showing the control mechanism for the inlet valve cam and illustrating it in reversing position.

Figure 9 is a layout view of the inlet valve cam sleeve.

Figure 10 is a similar layout view showing a modified form of cam lobes.

Figure 11 is a layout view similar to Figure 9 except showing the lobes arranged without axial spacing.

Figure 12 is a sectional view similar to Figures 3 and 8 showing a modified form of construction in which a cam for the transfer valve and the exhaust valve is connected with the intake valve.

cam operating means for simultaneous operation therewith.

Figure 13 is a layout view of the modified cam sleeve of Figure 12; and

5 Figure 14 is an enlarged sectional view of a connecting device shown in side elevation in Figure 12.

10 On the accompanying drawings, I have used the reference numeral 10 to indicate a power shaft. In the illustration of my invention, I have shown it in the form of a crank shaft having crank pins 12 and 14.

15 The power shaft 10 is journaled in suitable bearings, preferably of the ball or roller type (illustrated as plain bearings 16 on the drawings) which are supported by a crank case 18.

20 High pressure cylinders H1, H2, H3 and H4 are arranged radially around the power shaft 10 and suitably connected with the crank case 18. Low pressure cylinders L1, L2, L3 and L4 are also arranged radially around the power shaft and connected with the crank case.

25 On the drawings, I have illustrated four high pressure cylinders and four low pressure cylinders. Any feasible number of them may be provided, however, the greater the number the smoother and more turbine-like being the action of the motor. The essential consideration is that there shall be one low pressure cylinder for each high pressure cylinder and the two should be arranged as closely together as possible to minimize the travel of transferred steam from the high pressure cylinder to the low pressure cylinder.

30 Reciprocable in each high pressure cylinder is a high pressure piston 20. One of the high pressure pistons has a master connecting rod 22, while each of the other high pressure pistons has a secondary connecting rod 24.

35 Reciprocable in each low pressure cylinder is a low pressure piston 26. Pivoted to one of these is a master connecting rod 28, while pivoted to each of the others is a secondary connecting rod 30. The master connecting rods 22 and 28 are 40 rotatable on the crank pins 12 and 14, respectively, while the secondary connecting rods 24 and 30 are pivoted to the master connecting rods 22 and 28 respectively in the ordinary manner for motors of the radial type.

45 For each high pressure cylinder, I provide an intake valve cylinder 32 having bores 34 and 36. An inlet port 38 is provided for each valve cylinder 32. Steam or other expansible fluid pressure may be controlled by a throttle (not shown) and admitted through a manifold 40 and inlet pipes 42 to each port 38.

50 Each intake valve cylinder 32 is provided with an outlet port 44 which communicates with the adjacent high pressure cylinders. Between the 55 ports 38 and 44 a valve seat 46 is provided. A valve head 48 is adapted for seating thereagainst, the valve head and seat being beveled or of the poppet type and being normally constrained to engage each other by a spring 50 in a manner common in internal combustion engine construction. The valve head 48 is attached to a stem 45 extending slidably through the crank case 18 and having on its inner end a roller 47 for coaction with a valve cam later to be described.

55 On opposite sides of the valve head 48, I provide sealing pistons 52 and 54 reciprocable within the bores 34 and 36 of the valve cylinder 32. These, as well as the pistons 20 and 26, are provided with suitable piston rings to eliminate the 60 undesired escape of steam.

I provide poppet-like transfer valves 48a and exhaust valves 48b similar in construction to the intake valves 48.

65 Since all three valves are of similar construction, I will not go into detail as to the construction of the valves 48a and 48b, but on the drawings I show their associated parts designated by reference numerals similar to the reference numerals on the associated parts of the valve head 48 with the addition of the distinguishing characters a and b.

70 The inlet port 38a of the transfer valve 48a communicates with the high pressure cylinder, while the outlet port 44a thereof communicates with the low pressure cylinder. The inlet port 38b of the exhaust valve 48b communicates with the low pressure cylinder, while the outlet port 44b thereof communicates with exhaust piping 56.

75 For actuating the inlet valve heads 48, I provide an inlet valve cam sleeve 58. The cam sleeve 20 58 is slidably but non-rotatably mounted with respect to the power shaft 10, a suitable key 65 being provided for this purpose, or the cam sleeve 25 being splined on the power shaft. The cam sleeve 58 has circumferentially therearound a forward 25 direction lobe 60 and a rearward direction lobe 62. These lobes are shown in laid-out position in Figure 9. Their leading edges are indicated at 60a and 62a, respectively, while their trailing edges are indicated at 60b and 62b, respectively. 30

80 It will be noted that the trailing edges slant instead of extending substantially axially of the cam sleeve 58. The purpose of this is to provide intake cam lobes which can be adjusted axially and will vary the cut-off of the steam being admitted to the high pressure cylinders. For instance, when the cam sleeve 58 is slid to the position of Figure 3, the cut-off occurs substantially when the high pressure piston is half way on its down stroke. The down and up strokes of the 40 pistons are merely relative as the cylinders are arranged radially around the power shaft and throughout the specification and claims "down" is used to signify motion of the pistons toward the crank shaft, while "up" is used to signify motion away from the crank shaft.

85 When the cam sleeve 58 is adjusted toward the right, the cut-off point for the intake valves is delayed, thus admitting steam a longer proportion of the power stroke of the high pressure piston. Inversely, when the cam sleeve 58 is slid toward the left, the power stroke is shortened and cut-off may be advanced until a mere puff of steam enters each high pressure cylinder at the beginning of the power stroke of the piston 55 therein.

90 For sliding the cam sleeve 58 and thus controlling the cut-off of the intake valves, I form in the cam sleeve an annular groove 64 and I surround the groove with a collar 66. 60

95 Ball bearings 68 are then interposed between the groove and the collar to provide an anti-friction connection between the two. The collar 66 may be slid in any desired manner, a control lever 70 being illustrated for this purpose and 65 having a yoke 72 straddling the collar. The yoke 72 is provided with slots, such as indicated at 74 in Figure 12, for coaction with pins 76 extending from the collar. The lever 70 may be locked in various positions by means of the usual notched 70 sector 78 and coacting dog 80.

100 The lobes 60 and 62 may be axially spaced so as to provide between them a lobeless portion 59 on the cam sleeve 58 which permits all of the intake valves 48 to remain closed. This is a 75

neutral position preventing the admission of steam to any of the high pressure cylinders and allowing the motor to have a braking effect by reason of vacuous conditions produced in the high pressure cylinders when the high pressure pistons move downwardly with the valves 48 and 48a closed.

A modified construction is shown in Figure 11 where the lobeless space 59 is omitted so that 10 the cam sleeve, when adjusted to its central position, opens all the intake valves 48, thus permitting the full pressure of steam to act on all the pistons and quickly stop the motor.

This arrangement of intake valve actuator is 15 desirable where quick stops of the vehicle are required, such as on switching locomotives.

In Figure 10, I have shown forward and reversing cam lobes 61 and 63 having leading edges 61a and 63a similar to those in Figure 9, but having stepped trailing edges 61b and 63b. These 20 give an intake valve cut-off in definite steps rather than to any desired degree as when the types of lobes shown in Figures 9 and 11 are used.

25 With respect to the reversing lobes 62 and 63, the slanting and stepped trailing edges 62b and 63b can be omitted if desired where it is unnecessary to have any cut-off when the motor is operated reversely due to only infrequent reverse use.

The transfer valves 48a and the exhaust valves 48b are open the first portions only of the down and up strokes respectively of the low pressure pistons 26. This is for the purpose of clearing 30 the cylinders of steam under pressure, the valves remaining closed the remainder of the strokes for the advantage of trapping the remainder of the steam and compressing it for cushioning the upstrokes of the high pressure and low pressure 40 pistons, respectively.

This adds to the economy attained by the motor as the steam which provides the cushioning does not have to be provided by opening the intake valve 48 slightly before the high pressure piston 45 reaches top dead center and thus let in live steam which is the usual practice. Thus the steam that is already in the high pressure cylinder is trapped and is utilized rather than using newly generated steam from the boiler. For the 50 valves 48a and 48b, I provide a cam sleeve 82 secured to the power shaft 10 and having cam disks 84 and 86. The lobes for the cam disks 84 and 86 are indicated at 88 and 90, respectively. The lobes are not secured to the cam disks, but 55 are shiftable relative thereto.

In order to automatically shift the lobes relative to the cam disks, lost motion connections are provided consisting of slots 92 and pins 94. The slots and pins, as illustrated on the drawings, 60 permit substantially a quarter turn of shifting of the lobes relative to the cam disks as the lobes are shown as having an effective length of about ninety degrees so that the valves 48a and 48b are open about one-half of the upstrokes of the pistons 20 and 26. The length of these cams is 65 merely arbitrary as in practice it may be found that they should be longer or shorter than illustrated. Also, their length would vary for motors designed for different types of use.

70 From the foregoing construction, it will be obvious that whenever the power shaft 10 rotates in a direction opposite from the direction it previously rotated, the cam lobes 88 and 90 will be shifted with relation to the cam disks 84 and 75 86 by being held in stationary position by one

or more of the transfer valve stem rollers 47a and the exhaust valve stem rollers 47b. Thus automatic shifting of the transfer and exhaust valve cams is effected without any mechanical connection to the reversing lever 70.

It is possible however to so construct the transfer and exhaust valve cam mechanism that it can be controlled from the lever 70. I have shown such an arrangement in Figure 12.

A cam sleeve 96 is provided which is shiftable 10 by a forked lever 98 connected by a telescoping link 100 and a spring 102 to the reversing lever 70. Cam lobes 104, 106 and 108 are provided and arranged so that when the lobe 104 coacts with the roller 47a and the lobe 106 coacts with the 15 roller 47b, the valves 48a and 48b are set for rotation in one direction, while shifting the cam sleeve 96 to its right hand limit of motion in Figure 12 effects reversal.

In the position just mentioned, the lobe 106 20 would coact with the roller 47a, while the lobe 108 would coact with the roller 47b. As clearly shown on the drawings, the lobes 104 and 108 are one-hundred and eighty degrees apart with the respect to the lobe 106.

The telescoping link 100 and the spring 102 serve the purpose of placing the cam sleeve 96 in a neutral position when the cam sleeve 98 is in neutral position, but places the cam sleeve 96 in either the forward or rearward direction 30 position whenever the sleeve 98 is slightly moved to either side of its neutral position for operation of the motor either forwardly or reversely.

Thereafter, further swinging of the lever 70 will change the cut-off periods of the intake 35 valves 48, but the spring 102 will be either extended or compressed, thus leaving the lobes 106 and 104 or 108 properly aligned with the rollers 47a and 47b. Other mechanical mechanism, of course, can be substituted for that 40 shown to effect manual adjusting of all valves simultaneously.

To minimize vibration at high speed, the pistons 20 and 26 reciprocate in opposite directions and since they have different masses because the 45 high pressure cylinder bore is smaller than the low pressure cylinder bore, I preferably balance their weight by making the pistons 20 of heavy metal, such as cast iron or the like, and the pistons 26 of light metal such as aluminium, linite or 50 the like.

There are many advantages to the particular construction of steam motor which I have disclosed. The valves are arranged so that the steam travels always in one direction there- 55 through, thus eliminating successive changes in their temperature due to hot, high pressure steam passing one way through them and then cooled, low pressure steam passing the other way through the same valve.

All pressure of steam tending to move the valve is eliminated from it by providing the piston 52 of substantially the same area as the top of the valve head 48 and the piston 54 of substantially the same area as the bottom of the 65 valve head. By this arrangement, the spring 58 is the only factor tending to move the valve stem 45 toward the cam 56. However, if it is found desirable to aid or eliminate the spring, or to oppose it, the pistons 52 and 54 can be de- 70 signed accordingly.

By the use of the pistons 52 and 54 in the cylinder 32, all packing to prevent leakage is eliminated.

My particular compounding arrangement per- 75

mits direct transfer of steam from the high pressure cylinder to the low pressure cylinder, the transfer valves and passages being of adequate dimensions for providing an unobstructed passage for the transfer of the steam, through which the steam can be transferred with extreme ease.

Another decided advantage of this type of construction in a compound engine makes it possible to obtain a high starting torque such as 10 possible in ordinary types of steam engines only by the use of some simplifying device to admit steam to the low pressure cylinders directly. In my construction, the equivalent for a simplifying device is possible by extending the trailing edges 15 of the cam lobes 60 and 62 as illustrated in Figure 5a. The trailing ends are indicated at 60c and 62c.

In Figure 5, the cams 60 and 62, when adjusted for no cut-off, raise the intake valves 48 and 20 keep them open during a full half revolution. By the construction in Figure 5A it will be noted that the cams are longer circumferentially than in Figure 5, however, whereby it is possible to adjust them so that they are kept open longer than 25 a half revolution, or in other words, until after the high pressure piston starts on its upstroke. As soon as it starts on its upstroke, however, the transfer valve 48a is open so that the high pressure steam entering the high pressure cylinder is 30 transferred to the low pressure cylinder. This permits steam at boiler pressure to charge the low pressure cylinders wherein they act on the greater areas of the low pressure pistons and then thus start a much heavier load than when the 35 cam sleeve 58 is adjusted for ordinary operation and consequently cut off before the high pressure piston reaches its lower dead center.

The relative motion of each high pressure piston and its adjacent low pressure piston is illustrated diagrammatically in Figure 2. It will be noted that practically all high pressure pistons are at the opposite ends of their strokes with respect to the strokes of the low pressure pistons. This is quite important to provide a balanced running motor, yet a simple crank shaft with but 45 two cranks is necessary regardless of the number of cylinders used.

Even when the intake valve cam is adjusted for early cut-off, the motor operates smoothly because the low pressure pistons have the expansive pressure of the low pressure steam exerted on them during a full half revolution of the power shaft. Since there are four cylinders, the power strokes of the low pressure pistons overlap by forty-five degrees, thus insuring a very powerful but smooth rotation of the power shaft.

Even with only three cylinders, there would be a thirty degree overlap of the power impulses. The admission periods of the high pressure steam to the high pressure cylinders overlap whenever cut-off occurs later than one half the down stroke of the high pressure piston. For any adjustment of earlier cut-off, the steam, being compressible, continues to exert power on the high pressure 65 pistons even though the high pressure steam intake periods do not overlap.

The result in such construction is a turbine-like action on the power shaft which can be attained only by my method of compounding and 70 the radial arrangement of the cylinders with respect to the power shaft. This construction enables the operator to throttle down the motor to a much smaller consumption of steam and a further use of its expandable qualities without 75 undesirable pulsations or jerking effects experi-

enced with steam engines having slide valves and reverse eccentrics and linkage in the ordinary manner.

By arranging the cylinders radially around the power shaft and providing the cranks 12 and 14 at one-hundred and eighty degrees to each other, the power stroke of one low pressure piston is exerted on one side of the power shaft, while the power stroke of the opposite low pressure cylinder is exerted on the other side of the power 10 shaft. This gives a balancing effect which cannot be attained by any arrangement of cylinders in alignment. Such construction gives to the power shaft a rolling action from all sides, minimizing pressure on the bearings and consequent 15 frictional losses which waste useful power.

For economy's sake, the cylinders and valves should be covered with insulation to prevent the escape of heat. This, however, is not shown on the drawings and considerable condensation of 20 the parts to form a compact motor can also be made, the patent drawings being only for the purpose of illustration.

Changes in the cam arrangement and the method of controlling them, such as illustrated by 25 way of example on the drawings, and other changes may be made without departing from the real spirit and purpose of my invention, and it is my intention to cover by my claims, any modified forms of structure or use of mechanical 30 equivalents, which may be reasonably included within their scope.

I claim as my invention:

1. An expandible fluid pressure motor comprising a power shaft, a plurality of high pressure cylinders arranged radially therearound, a high pressure piston in each of said high pressure cylinders and operatively connected with said power shaft, a low pressure cylinder adjacent each high pressure cylinder, a low pressure piston in each 35 low pressure cylinder and operatively connected with said power shaft to move in a direction opposite its adjacent high pressure piston, means for admitting fluid pressure to said high pressure cylinders successively and means for transferring fluid pressure from each of said high pressure cylinders into its adjacent low pressure cylinder on the upstroke of the high pressure piston therein, said high pressure piston being of heavier material than said low pressure piston but both of them being of substantially the same weight to balance each other.

2. An expandible fluid pressure motor comprising a power shaft, a plurality of high pressure cylinders arranged radially therearound, a high 55 pressure piston in each of said high pressure cylinders and operatively connected with said power shaft, a low pressure cylinder adjacent each high pressure cylinder, a low pressure piston in each low pressure cylinder and operatively 60 connected with said power shaft to move in a direction opposite its adjacent high pressure piston, means for admitting fluid pressure to said high pressure cylinders successively during their downstrokes and for a part each of their upstrokes and means for transferring fluid pressure from each of said high pressure cylinders into its adjacent low pressure cylinder beginning at the start of the upstroke of the high pressure piston.

3. An expandible fluid pressure motor comprising a power shaft, a plurality of high pressure cylinders arranged radially therearound, a high pressure piston in each of said high pressure cylinders and operatively connected with said power shaft, a low pressure cylinder adjacent 70

each high pressure cylinder and a low pressure piston in each low pressure cylinder and operatively connected with said power shaft to move in a direction opposite its adjacent high pressure piston, said high pressure piston being of heavier material than said low pressure piston but both of them being of substantially the same weight to balance each other.

4. An expandible fluid pressure motor comprising a power shaft, a high pressure cylinder, a high pressure piston therein operatively connected with said power shaft, a low pressure cylinder, a low pressure piston therein operatively connected with said power shaft to move in a direction opposite said high pressure piston, means for admitting fluid pressure to said high pressure cylinder during the downstroke of the piston therein and for a part of the upstroke of said high

pressure piston and means for transferring fluid pressure from said high pressure cylinder into said low pressure cylinder beginning at the start of the upstroke of the high pressure piston.

5. An expandible fluid pressure motor comprising a power shaft, a high pressure cylinder, a high pressure piston therein and operatively connected with said power shaft, a low pressure cylinder and a low pressure piston therein and operatively connected with said power shaft to move in a direction opposite said high pressure piston, said high pressure piston being of material having a greater specific gravity than the specific gravity of the material of said low pressure piston, but both of them being of substantially the same weight to balance each other.

CARL EMMIT BISHOP.
